(57) **CLAIM**

(21) Appl. No.: **29/268,747**

I claim the ornamental design for an embossing for a multipanel garage door, as shown and described.

(22) Filed: **Nov. 10, 2006**

DESCRIPTION

(51) LOC (9) Cl. **25-02**

FIG. 1 is a front perspective view of an embossing for a multipanel garage door showing my new design; and,
FIG. 2 is a cross sectional view taken along line 2—2 of FIG. 1.

(52) U.S. Cl. **D25/48**

(58) **Field of Classification Search** D25/48,
D25/138; 160/98, 99, 120, 201

See application file for complete search history.

The broken lines depicting garage door sections, and the various components thereof, represent environmental elements only, and form no part of the claimed design.
